(57) **CLAIM**

The ornamental design for a display screen with an animated graphical user interface for medical software, as shown and described.

DESCRIPTION

FIG. 1 is a first image of at least a portion of a display screen with an animated graphical user interface for medical software showing the new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof;

FIG. 10 is a tenth image thereof;

FIG. 11 is an eleventh image thereof;

FIG. 12 is a twelfth image thereof;

FIG. 13 is a thirteenth image thereof; and,

FIG. 14 is a fourteenth image thereof.

The broken lines showing at least a portion of the display screen and portions of the graphic user interface illustrate portions of the article and form no part of the claimed design. These broken lines form no part of the claimed design.

The appearance of the animated graphical user interface transitions from FIGS. 1-14. The process or period in which one image transitions to another forms no part of the claimed design.
